UNITED STATES PATENT OFFICE.

MAGNUS E. WIDELL, OF MAYWOOD, ILLINOIS, ASSIGNOR TO AMERICAN CAN COMPANY, OF NEW YORK, N. Y., A CORPORATION OF NEW JERSEY.

CAN-BODY-MAKING MACHINE.

1,206,395.

Specification of Letters Patent. Patented Nov. 28, 1916.

Application filed April 8, 1912. Serial No. 689,418.

To all whom it may concern:

Be it known that I, MAGNUS E. WIDELL, a citizen of the United States, residing in Maywood, in the county of Cook and State of Illinois, have invented a new and useful Improvement in Can-Body-Making Machines, of which the following is a specification.

This invention relates to improvements in can body making machines.

The object of the invention is to provide an automatic can body making machine of a simple, durable and efficient construction, by means of which beaded, necked-in, curled and flanged can bodies may be cheaply and rapidly manufactured, and a machine which preferably performs all of said operations practically simultaneously.

The invention furthermore consists in the improvements in the parts and devices and in the novel combinations of the parts and devices herein shown and described or claimed.

A machine embodying the invention comprises in co-operative combination, a body former horn furnished with an extension for supporting the formed can bodies in position for operating thereon of the flanging, necking-in and beading dies, wings or folding devices for forming the bodies, a seam bumper, a reciprocating, external necking-in die, an internal necking-in die mounted on the end of the horn extension and co-operating with the external necking-in die, a plurality of opening and closing or radially reciprocating beading dies mounted on the end of the horn extension, a reciprocating conveyer for feeding the can body blanks to the body forming mechanism and advancing the formed can bodies along the horn extension to the necking-in, beading and flanging dies, a pair of reciprocating sectional flanging dies co-operating with the horn extension, a pair of reciprocating, sectional can body shape retaining dies also co-operating with the horn extension to prevent buckling of the can body, and a can body ejector.

A further object of my invention is in the arrangement and disposition of certain structural features which have a direct bearing on the efficiency and accuracy of the operations of the machine. One of these features comprises the tension and alinement rods connecting the several frame

members constituting the mechanism supports. It is very essential in producing accurate work that vibration be eliminated from the machine and that the alinement and adjustment of the body forming mechanism, the flanging, and the necking in devices be maintained during operation; otherwise imperfect work, excessive wear of dies and operating parts and premature fatigue of the metal constituting the frame of the machine lead to short life and unsatisfactory service.

The other feature constitutes the application of yielding devices to the bearings carrying the operating shafts. These yielding or cushioning devices are sufficient to hold the shafts in their bearings during all normal operations; but relieve the shafts, connecting parts and frame work from undue and abnormal strains occasioned by over-thick, misplaced or damaged stock or from misadjustment.

In the drawing, forming a part of this specification, Figure 1 is a side elevation of a machine embodying the improvements, parts of the machine being broken away. Fig. 2 is a horizontal longitudinal section, taken substantially on the line 2—2 of Fig. 1. Fig. 3 is a vertical section, taken on the line 3—3 of Fig. 1. Fig. 4 is a vertical cross section, taken on the line 4—4 of Fig. 1. Fig. 5 is a transverse, vertical section, taken on the line 5—5 of Fig. 1. Fig. 6 is an enlarged, detail end view of the horn extension, a part of the internal necking-in die being broken away. Fig. 7 is a longitudinal, partial section, upon an enlarged scale, of the end of the horn extension, taken on the line 7—7 of Fig. 6, and showing also the external necking-in die and the flanging and shape retaining dies, and Fig. 8 illustrates a modified form of necking-in mechanism.

In the drawings, 10 represents a suitable base adapted to support the various parts of the mechanism. Mounted on the upright 11 is a body former horn 12, and adjacent thereto are wings or folding arms 13 adapted to bend the previously hooked body blank around the horn, said wings 13 being operated by rods 14 and lever 15 keyed to an oscillating shaft 16. Co-operating with the folding arms or wings 13 is a bumper 17 adapted to compress the seam in the can body, said bumper being operated from a

crank 18 on a cross shaft 19. The body forming mechanism may be of any suitable or well known type, and coöperating therewith and adapted to feed the previously hooked can body blanks from the edging mechanism (not shown) is a conveyor 20, provided with fingers 21 adapted to reciprocate the blanks from the edging mechanism to the body forming devices, and from the body forming devices to the flanging, necking-in and beading stations. The horn 12 is provided with an extension 22, which may be formed either separately from or integral with the body former horn 12. The can body supporting horn or extension 22 is provided at its outer end with an internal necking-in die 23, secured to the extension in any suitable manner, as by means of bolts 24. The diameter of the internal necking-in die 23 corresponds to the desired internal diameter of the necked-in portion of the can body. Also mounted on the end of the can body supporting horn 22 are radially reciprocating beading dies 25, adapted to move inwardly and outwardly and operated by means of a wedge 26, having a plurality of faces 27 corresponding to the number of sectional beading dies 25, said wedge 26 being normally outwardly pressed by means of a spring 28 seated in a pocket 29 in the horn extension 22. Each of the beading dies 25 is yieldingly held in position by means of a spring 30, seated in a groove 31 formed partly in the horn extension 22 and partly in the member 25. The horn extension 22 is furthermore provided with a circumferentially extending groove 32, in which are adapted to be seated a pair of oppositely reciprocating flanging dies 33, each provided with a groove 34 and a limiting wall 35. Each of these flanging dies 33 is mounted upon a reciprocating slide 36, slidably mounted in ways 37, and operated through means of a link 38 and lever 39 keyed to shaft 40, each of said shafts 40 being oscillated by means of a bell crank 41, said bell cranks being connected together by a link 42, and one of said bell cranks 41 being oscillated by a link 43, pivoted to a crank arm 50, keyed to an oscillating shaft 45. Also mounted on each of the slides 36 is a sectional mold or die 46, conforming in shape to the can body being operated upon and adapted to engage the outer side of the can body during the flanging, beading and necking-in operations and retain the body in its proper shape and prevent buckling during the flanging and necking-in operations. Each of the dies or molds 46 is furthermore provided with a recess 47 to provide clearance for the flange formed on the can body. Each of the molds or dies 46 is furthermore provided near its outer edge with a groove or recess 48, adapted to coöperate with the beading dies 25. A horizontally reciprocating

slide 49 is located in line with the end of the body former horn extension, and has mounted thereon an external necking-in die 50, the same being provided with a curling die portion 150, when desired and adapted to coöperate with the internal necking-in die 23, said die 50 being secured to the slide by means of a hollow sleeve 51 and nut 52. Mounted in the external necking-in die or plunger 50 is an ejector 53, operated by means of a plunger 54 secured thereto, said ejector 53 being normally retained within the die 50 by means of a spring 55, engaging a washer 56 on the plunger 54. The inner end of the plunger or rod 54 is also adapted to operate the wedge 26, and to thus move the beading dies 25 outwardly. The ejector 53 is operated by means of a lever 57, pivoted to the slide 49 and adapted to be engaged by an adjustable stop 58 on a stationary part of the machine. The slide 49 is reciprocated from a crank 59 on a cross shaft 60, said cross shaft 60 being supported in a plurality of yieldingly mounted bearings 61. By providing these yieldingly mounted bearings 61, the machine automatically accommodates itself to various lengths of can bodies without destroying any of the necking-in or flanging dies. The cross shaft 60 is operated from a longitudinally extending shaft 62, which derives its power from the cross shaft 19 through means of a diagonally disposed shaft 63.

Mounted on the shaft 60 is a cam 64, having a cam groove 65 therein, adapted to operate and oscillate the shaft 45 through means of a lever 66 keyed thereto, and having a roller 67 engaging in the groove 65.

The machine is furthermore provided with a chute 68 located adjacent to the end of the body former horn extension. In the modified form shown in Fig. 8, the body former extension 69 has formed integrally therewith an internal necking-in die 70, adapted to coöperate with an external necking-in die or plunger 71, provided with a curling die portion 171, in this form the beading dies being omitted.

In the operation of the machine, a hooked or edged blank is fed by the reciprocating feeder to the body forming mechanism where the can body blank is formed into a body and the seam bumped, after which the can body is pushed along the horn extension to a point beyond the flanging dies, while the latter are in their outermost or open position, after which the flanging dies are moved inwardly into engagement with the groove in the horn extension. The slide carrying the external necking-in die is then reciprocated toward the horn and the ejector plate 53 within the necking-in die will thereupon engage the outer edge of the can body and push the same against the flanging dies, thereby forming a flange and at the

same time the beading dies will be operated by means of the plunger 54 engaging the wedge 26, so that all three operations of flanging, necking-in and beading are accomplished practically simultaneously. After these operations, the flanging dies and die molds are withdrawn and the necked-in can body will be pulled from the horn extension by the external necking-in die and will be ejected therefrom when the lever 57 engages the stop 58, whereupon the can body will drop down into the chute 68.

The machine as shown is adapted to operate on cylindrical can bodies, but it will be obvious that the same may be easily adapted to operate on can bodies of other forms. The drawing illustrates one form of the invention, but it will be understood that the same is merely illustrative, and that many changes and variations may be made in the various parts and details thereof without departing from the spirit of the invention, and all such changes and modifications are contemplated as fairly falling within the scope of the appended claims.

What is claimed is:

1. In a machine of the class described, in combination, a can body supporting horn, beading dies and necking-in mechanism including a reciprocating external necking-in die.
2. In a machine of the class described, in combination, a can body supporting horn, beading dies, an internal necking-in die secured to the end of said horn and a reciprocating external necking-in die.
3. In a machine of the class described, in combination, a can body supporting horn, expandible beading dies mounted on the end of said horn and coöperating external and internal necking-in dies.
4. In a machine of the class described, in combination, a can body supporting horn, beading dies, necking-in mechanism and flanging mechanism, said dies and mechanisms adapted to operate on a can body while on the supporting horn.
5. In a machine of the class described, in combination, a can body supporting horn, a conveyer for moving can bodies along said horn, flanging dies and beading dies, said sets of dies being adapted to operate on a can body while the same is on the supporting horn.
6. In a machine of the class described, in combination, a can body supporting horn, a conveyer adapted to move can bodies along said horn, flanging dies and coöperating external and internal necking-in dies, said sets of dies being adapted to operate on a can body while the same is on the horn.
7. In a machine of the class described, a can body supporting horn, a can body conveyer, a reciprocating necking-in die or plunger and beading dies, said dies being

adapted to operate on a can body while the same is on the supporting horn.

8. In a machine of the class described, in combination, a can body supporting horn, a reciprocating can body conveyer, a reciprocating necking-in die or plunger, an internal necking-in die mounted on the end of said horn and beading dies, all of said dies being adapted to operate on a can while the same is on the horn.

9. In a machine of the class described, in combination, a can body conveyer, necking-in mechanism including a reciprocating external necking-in die or plunger, a can body ejector mounted in said necking-in die, means for operating said ejector, and beading dies.

10. In a machine of the class described, in combination, a can body supporting horn, beading devices and a plurality of reciprocating sectional flanging dies.

11. In a machine of the class described, in combination, a can body supporting horn, an internal necking-in die mounted on the end of said horn, a reciprocating external necking-in die or plunger, and a plurality of movable, sectional flanging dies.

12. In a machine of the class described, in combination, a can body supporting horn, beading devices, a reciprocating external necking-in die, a coöperating internal necking-in die on the end of said horn and a plurality of movable, sectional flanging dies.

13. In a machine of the class described, in combination, a can body supporting horn, a plurality of movable sectional flanging dies and a plurality of opening and closing beading dies mounted on the end of said horn.

14. In a machine of the class described, in combination, a stationary can body supporting horn, a conveyer adapted to move can bodies along said horn, and a plurality of sectional flanging dies movable into and out of engagement with said horn.

15. In a machine of the class described, in combination, a can body supporting horn, a conveyer adapted to move can bodies along said horn, said horn being provided with a groove extending therearound, a pair of reciprocating, sectional flanging dies movable into and out of engagement with said horn and adapted to be seated in said groove.

16. In a machine of the class described, in combination, a can body supporting horn, a reciprocating can body conveyer, movable sectional flanging dies and movable sectional external body die molds.

17. In a machine of the class described, in combination, a can body supporting horn having a groove therearound, a plurality of reciprocating sectional flanging dies movable into and out of engagement with said horn and adapted to be seated in the groove,

- and a plurality of reciprocating sectional external body die molds.
18. In a machine of the class described, in combination, a can body supporting horn, 5 a plurality of opening and closing beading dies mounted on the end of said horn, a plurality of sectional flanging dies movable into and out of engagement with said horn, and a plurality of movable, sectional, external 10 body die molds, said molds being provided with beading grooves adapted to coöperate with said beading dies.
19. In a machine of the class described, in combination, a can body supporting horn, 15 beading devices, a reciprocating external necking-in die or plunger, a coöperating internal necking-in die mounted on the end of said horn, said necking-in dies having coöperating die curling portions, and a plurality of movable, sectional flanging dies.
20. In a machine of the class described, in combination, a can body supporting horn, beading devices, a reciprocating external necking-in die or plunger, a coöperating internal necking-in die mounted on the end of 25 said horn, a plurality of movable, sectional flanging dies, and a plurality of movable sectional body die molds.
21. In a machine of the class described, 30 in combination, a can body supporting horn, beading devices, a reciprocating external necking-in die or plunger, a coöperating internal necking-in die mounted on the end of said horn, a plurality of movable, sectional 35 flanging dies and a plurality of movable sectional body die molds, said molds being provided with grooves adapted to coöperate with said beading dies.
22. A can body supporting horn having a 40 circumferential groove therearound, a conveyer adapted to move can bodies along said horn, a pair of oppositely movable reciprocal slides, sectional flanging dies mounted on said slides and adapted to be seated 45 in said groove, and a pair of sectional external body die molds also carried by said slides.
23. In a machine of the class described, 50 a can body supporting horn having a groove therearound, a conveyer adapted to move can bodies along said horn, a pair of reciprocating sectional flanging dies adapted to be seated in said groove, a reciprocating external necking-in die, a coöperating internal 55 necking-in die on the end of said horn, and an ejector located within said external necking-in die.
24. In a machine of the class described, 60 a can body supporting horn, movable sectional flanging dies, said horn being provided with an internal necking-in die on the end thereof, a reciprocating slide having an external necking-in die or plunger thereon, 65 means for reciprocating said slide, said means comprising an operating shaft dis-
- posed at right angles to the line of movements of the slide, said shaft being supported in yieldable sectional bearings.
25. In a machine of the class described, in combination, a can body supporting horn, 70 flanging mechanism and necking-in mechanism, said mechanisms being adapted to operate simultaneously on a can body.
26. In a machine of the class described, in combination, a horn having a stationary 75 extension, and flanging mechanism, including dies having grooves and limiting walls thereon, said mechanism being so arranged that the flanging operation is performed while the can body is on the horn extension 80 and prevented from rotation thereon.
27. In a machine of the class described, in combination, a horn having a stationary extension, and can body beading mechanism, the beading mechanism being so arranged 85 that the can bodies are beaded while on the horn extension and prevented from rotation thereon.
28. In a machine of the class described, in combination, a horn having a stationary extension, and can body curling mechanism, 90 the curling mechanism being so arranged that the can bodies are curled while on the horn extension and prevented from rotation thereon.
29. In a machine of the class described, in combination, a horn having an extension, flanging mechanism including a reciprocating necking-in die and can body necking-in mechanism, the flanging and necking-in 100 mechanism being so arranged that the flanging and necking-in operations are performed while the can bodies are on the horn extension.
30. In a machine of the class described, 105 in combination, a horn having an extension, can body flanging mechanism and curling mechanism, said mechanism being so arranged that the flanging and curling operations are performed while the can body is 110 on the horn extension.
31. In a machine of the class described, in combination, a horn having an extension, can body flanging mechanism, can body necking-in mechanism and can body beading 115 mechanism, said flanging, necking in and beading mechanisms being so arranged that the flanging, necking in and beading operations are performed while the can body is on the horn extension.
32. In a machine of the class described, 120 in combination, a horn having an extension, flanging mechanism, necking-in mechanism and curling mechanism, said flanging, necking-in and curling mechanisms being so arranged 125 that the flanging, necking-in and curling operations are performed while the can body is on the horn extension.
33. In a machine of the class described, in combination, a horn having an extension, 130

flanging mechanism, necking-in mechanism, beading mechanism and curling mechanism, said flanging, necking-in, beading and curling mechanisms being so arranged that the flanging, necking-in, beading and curling operations are performed while the can body is on the horn extension.

34. In a machine of the class described, in combination, a horn having an extension, can body flanging mechanism, beading mechanism and curling mechanism, said flanging, beading and curling mechanisms being so arranged that the flanging, beading and curling operations are performed while the can body is on the horn extension.

35. In a machine of the class described, in combination, a horn having an extension, necking-in mechanism and curling mechanism, said necking in and curling mechanisms being so arranged that the can bodies are necked in and curled while the can body is on the horn extension.

36. In a machine of the class described,

in combination, a horn or mandrel provided with an internal necking-in die at one end thereof and a movable, external necking-in die coöperating therewith, and a flanging die located at a point removed from the end of the horn, and provided with a flanging groove adjacent to and extending around the horn.

37. In a machine of the class described, in combination, a horn or mandrel provided with an internal necking-in die at one end thereof and a movable, external necking-in die coöperating therewith, and a flanging die located at a point removed from the end of the horn, and provided with a flanging groove adjacent to and extending around the horn, said flanging die comprising a plurality of movable plates, each having a section of the flanging groove formed therein.

MAGNUS E. WIDELL.
